ROLLER PLATEN CONTROL IN ADDRESSING
MACHINES

Lewis S. Prosser, Jr., Shawnee, Kans.

Application November 16, 1950, Serial No. 195,999

4 Claims. (Cl. 101—56)

1

This invention relates to printing machines of the kind using a platen movable automatically to and from a printing position with respect to a printing device having a number of lines of type thereon for producing the characters of the device upon a sheet or form each time the platen moves through its complete cycle of operation.

Printing devices to which this invention relates and in present use throughout the country are capable of sequentially moving a plurality of printing devices past a printing position and holding the same in such position momentarily while an impression is made therefrom or for longer periods of time whereby a number of impressions may be made.

There has also been provided in such machines structure capable of permitting imprinting from certain portions of the device during one cycle of movement of the platen and from the remaining type characters during a second complete cycle of operation of the platen mechanism. For instance, it is possible through structure heretofore placed in use to print the name and address of an addressee from a printing device having such type thereon as the platen moves across the sheet of material being printed leaving a salutation also forming a part of the printing device unused, whereby envelopes may be addressed during one cycle of operation and the heading of a letter prepared including the salutation during an alternate cycle of operation of the machine.

In other instances printing devices are each provided with a plurality of rows of type and it is possible through mechanism heretofore provided to print from a single selected row and thereupon permit the device to pass from the printing position. Accordingly, if it is desired to print all of the rows of characters separately from a given printing plate, it is necessary to pass the same through the printing machine a number of times equal to the number of rows of type characters thereon.

Such printing machines are universally used to address mailing material in the nature of advertising literature wherein only the street address of the addressee is placed thereon. Such literature is commonly forwarded to the "occupant" only in a given city and consequently the pieces of literature are passed through the machine but once and the street address only printed thereon.

Since as above indicated it is necessary to direct the printing devices through the machine

2

as many times as there are addresses thereon, the task of preparing advertising literature for mailing is great and further, the addressed material is arranged in a haphazard fashion not conducive to easy handling by the Post Office Departments.

It is the most important object of the present invention therefore, to improve upon printing machines of such character whereby to render the same operable in "picking up" in a predetermined order all of the rows of type appearing upon a given printing device, while the same is held in a printing position and prior to release thereof and directing of a second printing device to the printing position.

Another important object of this invention is to provide in a printing machine a specially formed cam disc capable of controlling the operation of the machine and particularly the platen thereof to render the same effective in printing in step-by-step fashion from each of a number of rows of type in predetermined order while the printing plate having the type thereon remains in the printing position.

A further object of this invention is the provision of a cam member for controlling the movement of a reciprocable roller platen in a printing machine in such manner as to address a large number of advertising circulars so as to arrange the same in order with respect to the street addresses printed thereon whereby the circulars may be bound together for mailing in a number of bundles corresponding to particular mailing zones that form a part of the present-day mailing system in the larger cities.

A still further object of the present invention is to improve upon printing machines by the provision of a number of removable cam discs each corresponding to a particular embossed printing device for rendering the printing machine operable as above set forth without the necessity of otherwise modifying the machine or requiring skill on the part of the operator in making the desired change-over.

Other objects of this invention will be made clear or become apparent as the following specification progresses, reference being had to the accompanying drawings, wherein:

Figure 1 is an elevational view looking from the left hand end of a printing machine to which the present invention relates as the same is passed from its normally front side, parts being in section and illustrating the platen mechanism

3
thereof together with the improvements in platen control apparatus made pursuant to the present invention.

Fig. 2 is a view similar to Fig. 1 illustrating the various parts of the platen mechanism and control therefor in a different operating position.

Figs. 3 to 6 inclusive are diagrammatic views illustrating the positions which certain of the parts of the platen mechanism assume in the various cycles of operation of the platen mechanism through use of the control apparatus illustrated in Figs. 1 and 2.

Fig. 7 is a cross-sectional view taken on line VII—VII of Fig. 1.

Fig. 8 is an elevational view of a modified form of cam disc and ratchet control apparatus made according to the present invention.

Fig. 9 is a cross-sectional view taken on line IX—IX of Fig. 1.

Fig. 10 is a cross-sectional view taken on line X—X of Fig. 9; and

Fig. 11 is a cross-sectional view taken on line XI—XI of Fig. 9.

Reference is made to U. S. Letters Patent No. 2,359,850 and No. 2,359,849, both dated October 10, 1944, for a full understanding of the complete construction and operation of a printing machine to which the present invention pertains. In all of the several forms of the machine set forth in the latter, a roller platen is provided capable of being rolled across a sheet or form as the same moves through a reciprocable path of travel. Rotative, or more appropriately oscillatory movement, is imparted to the platen through an elongated rack and associated gearing. In one form the rack is rendered manually adjustable and in another form automatically adjustable to vary the initial position of the roller platen at one end of its cycle of operation.

The hollow roller platen shown in the drawings hereof and broadly designated by the numeral 10, is mounted for rotation on a horizontal pin 12 that is in turn supported by a pair of spaced, swingable links, one only being shown and designated by the numeral 14. Platen 10 adapted for use with the control unit hereof is provided with a single, relatively narrow printing face or strip 16 extending longitudinally thereof in parallelism with pin 12.

Printing devices used with the machine include relatively flat, metallic plates having rows of type embossed therein and appearing in relief on one face thereof. Such plates may be fed successively to and from a printing position that includes an anvil 18. An inked ribbon overlies the printing plate and sheets or forms to be printed are passed in sequence over the ribbon to receive a printing impression by operation of platen mechanism 20 that includes platen 10, pin 12 and links 14.

There is provided upon the uppermost face of a table (not shown), a C-shaped frame that includes an upper arm 22 for supporting platen mechanism 20 above anvil 18. Arm 22 is provided with a pair of spaced horizontal tracks on a plate 23, one of which is identified by the numeral 24 for supporting a reciprocable carriage 26 through the medium of rollers 28 and 30.

Reciprocation is imparted to the carriage 26 by means of a continually rotating shaft having an actuating eccentric and clutch structure (all not shown) for rocking a shaft 32. An arm 34 fixed to shaft 32 and swingable from the position shown in Fig. 1 to that of Fig. 2 connects

4
with carriage 26 by means of links 36, pivoted at 38 to arm 34 and at 40 to carriage 26.

Platen 10 is mounted on carriage 26 for movement to and from a retracted position shown in Fig. 1 by means of toggle constructions 42 each including a pair of links 44 and 46 pivotally joined by pin 48. Link 44 is pivoted to carriage 26 by a shaft 50 and the link 46 rotatably receives the pin 12.

An elongated rack 52 having teeth 54 is in mesh with a gear 56, in turn joined with a gear 58. One of the links 14 supports three pinions 60, 62 and 64 in intermeshing relationship, pinion 60 being mounted for rotation by gear 58 and pinion 64 being coupled with platen 10. Consequently, as carriage 26 is reciprocated by links 36 with respect to rack 52, oscillatory motion is imparted to platen 10.

An elongated bar 66 is operably joined to shaft 50 at one end thereof and to the arm 34 by means of a slot 68 in bar 66 and a pivot pin 70. As carriage 26 reciprocates and as arm 34 is rocked, toggle 42 operates to move the platen 10 from the position shown in Fig. 1 to substantially that shown in Figs. 3 to 6 inclusive.

It is seen therefore, that the initial position of rack 52 with respect to movement on its longitudinal axis determines the position of roller 10 and particularly the strip 16 at the time the latter moves to a position in contact with a sheet overlying an embossed plate on anvil 18.

Rack 52 is provided with a second set of teeth 72 in mesh with a gear 74 secured directly to an actuating shaft 76. Shaft 76 is mounted in a bracket 78 within a housing 80 and a plate 82 on shaft 76 holds rack 52 against gear 74. A web 83 is provided with a guide groove 84 for the rack 52.

A spring 86 coiled about shaft 76 has one end 40 thereof attached to the latter and the opposite end secured by pin 88 to bracket 78 as shown in Fig. 11. Spring 86 tends to rotate shaft 76 clockwise, viewing Figs. 1 and 2, to bias the rack 52 in a direction away from carriage 26.

45 A housing 80 secured to one wall of the housing 80 by screws 92 supports an arm 94 by means of a pivot pin 96, arm 94 having gear teeth 98 on the lowermost arcuate edge thereof. A pinion 100 in mesh with teeth 98 is secured to shaft 76 50 to rotate the latter and shift rack 52 when swinging movement is imparted to arm 94.

In accordance with the present invention, a special disc 102 is provided to swing arm 94 against the action of spring 86, and therefore, the single printing strip 16 on roller platen 10. Disc 102 is rotatably secured to a bolt 104 joining housings 80 and 90, along with a ratchet wheel 106 joined with disc 102 by a hub 108 and having eight equally spaced teeth 110. Screws 112 in bolt 104 and pin 96 hold a cover plate 114, the disc 102 and wheel 106 in place.

A pawl 116 pivoted at one end to a cross pin 118 on arm 94 has a pin 120 on its opposite end biased against teeth 110 of wheel 106 by a spring 122.

Movement of arm 94 to the right, viewing Figs. 1 and 2, causes ratchet wheel 106 to be stepped in a counter-clockwise direction. Similarly, disc 102 rotates to the succeeding cam surface. Obviously, the swinging movement of arm 94 must be controlled to return the roller 140 to the succeeding cam surface of disc 102, since, during the stepping action, the roller 140 will have been displaced substantially farther than the minimum radius of the succeeding cam surface. By

the action of spring 86, wheel 74, meshed with arm 94, is kept biased against the cam surface of disc 102. The motion imparted to rack 52 and associated elements by such rotation of wheel 74 is of no importance since such rotation takes place during the repositioning cycle of all components, and the rack 52 is repositioned during each cycle of operation.

The disc 102 is divided at its periphery into two sets of cam faces: 124—126—128—130 and 132—134—136—138, successively engageable with a roller 140 on arm 94 as disc 102 is stepped in an anti-clockwise direction (viewing Figs. 1 to 6 inclusive) by pawl 116. Each set of cam faces is capable of causing printing from four rows of printing plate type. Thus, for each complete rotation of disc 102, eight addresses from two plates may be printed.

The distances between face 124 and axis 104 is equal to the distance between face 132 and axis 104. Other identical pairs with respect to radial distances from axis 104 include faces 126 and 134; 128 and 136; and 130 and 138. However, the distances progressively decrease clockwise from face 124 to face 130 and from face 132 to face 138. In other words the radial disposition of face 126 is slightly less than that of face 124, etc. Such decrease is progressive and gradual, the radii being for example as follows:

	Inches
Faces 124 and 132	1 $\frac{3}{16}$
Faces 126 and 134	1 $\frac{1}{16}$
Faces 128 and 136	1 $\frac{7}{16}$
Faces 130 and 138	1 $\frac{9}{16}$

In operation, the printing machine is pre-set to hold an embossed printing plate having four rows of addresses thereon on anvil 18 for four consecutive cycles of operation of platen 10 before it is released and replaced by another plate. On swinging movement of arm 34 from the position shown in Fig. 1 to that of Fig. 2 and return carriage 26 will be reciprocated along tracks 24 by link connection 36. Simultaneously platen 10 will be extended from the position shown in Fig. 1 to an extended position as shown in Figs. 3 to 6 inclusive as it approaches anvil 18.

Also, during each such operation, arm 34, acting through pawl 116 will actuate wheel 106 to advance disc 102 one step.

The stepping of disc 102 actuates arm 94 and wheel 74 to cause lateral displacement of rack 52. As previously shown, this displacement of rack 52 affects the positioning of strip 16 due to intermeshing of teeth 54, and gears 56, 58, 60, 62 and 64.

Consequently, the disposition of operating face 16 of platen 10 at the moment of reaching the printing position with respect to anvil 18 depends entirely on the position of rack 52 as controlled by cam 102.

When cam face 124 is in engagement with roller 140, as shown in Figs. 1 and 3, the arm 94 is swung further to the right than after disc 102 has been stepped to successively move faces 126, 128 and 130 into engagement with roller 140. (See Figs. 4, 5 and 6.) Figs. 2 and 6 correspond so far as the position of disc 102 is concerned.

Accordingly, as arm 94 is progressively and gradually moved in a direction away from carriage 26, rack 52 will be shifted, changing the starting position of platen 10 as it commences its oscillatory motion. When cam face 124 engages roller 140, one of the rows of type on a printing plate will become effective with strip 75

16. When cam face 130 engages roller 140, the fourth row of type operates to print an address or other matter. Obviously, the same operation takes place with cam faces 132—134—136—138 on the next following printing plate.

Let it be assumed that a first plate contained the following:

824 Park Avenue
826 Park Avenue
828 Park Avenue
830 Park Avenue

And, assume the next succeeding plate had the following rows of type:

832 Park Avenue
834 Park Avenue
836 Park Avenue
838 Park Avenue

In the absence of cam disc 102, the plates would be advanced through the machine to pick up 824 Park Avenue, 832 Park Avenue, etc., until all plates had each been fed through the machine on a setting to print from the top line thereof. Thereupon, all plates would be again fed to print 826 Park Avenue, 834 Park Avenue, etc. Consequently, each plate must be fed four times to produce at least one impression from all four rows of type.

30. However, with cam disc 102 the first plate is held in printing position for four cycles of operation of platen 10, the cam faces controlling strip 16 to print as follows:

Cam face 124—824 Park Avenue
Cam face 126—826 Park Avenue
Cam face 128—828 Park Avenue
Cam face 130—830 Park Avenue

The first plate is then released and the next plate is held for the following results:

Cam face 132—832 Park Avenue
Cam face 134—834 Park Avenue
Cam face 136—836 Park Avenue
Cam face 138—838 Park Avenue

As the material, such as advertising circulars, emanates from the machine, it will be arranged in order, ready for mailing, and can be quickly handled in postal zones lessening the time consumed for dispatching after addressing.

50. Further, the time and labor consumed in directing the plates through the machine is reduced tremendously since all four addresses are printed from each plate before release thereof and it need not be again advanced to a position above anvil 18 for a given bundle of mailing material.

It is understood that in connection with the use of a single platen strip 16, disc 102 may be varied to accommodate printing plates having differing numbers of rows of type formed thereon.

For instance in Fig. 8 there is shown a modified disc 200 having nine active peripheral faces 202, 204, 206, 208, 210, 212, 214, 216 and 218. Face 202 is closest radially to the axis of disc hub 220, the radii progressively increasing as face 218 is approached. A ratchet wheel 222 therefore, has a corresponding number of teeth 224.

70. When disc 200 and wheel 222 are placed in use, single printing plate having nine rows of type thereon may be held until cam disc 200 has made a complete revolution, during which time printing may take place from all nine rows.

It is now apparent that a tremendous improve-

ment has been made in printing machines of the type set forth in the above mentioned patents. The need for control members of this character is great and large numbers of circul-
lars and other matter may be addressed or other-
wise printed in less time and with saving in
labor not made possible with control means here-
tofore known. Facilitating in handling for mailing
alone warrants equipping each such print-
ing machine with one or more cam disc and
ratchet-wheel assemblies in accordance with the
nature of the printing devices used.

It is particularly notable that in using a print-
ing machine having the novel cam mechanism
of this invention as a part thereof, the operator
may switch from plates having four lines of type
thereon to plates having nine lines for instance
by merely replacing the cam and without the
necessity of changing the platen. In other words,
plates having an indefinite number of lines of
type thereon may be utilized with a like number
of cams, all without having to provide for differ-
ing platens and changing the same for each op-
eration.

It is further notable that while the two cams
chosen for illustration herein have their active
faces so arranged as to print from the lines of
type on the printing plate in consecutive order,
such is not necessary to the broad principles of
operation hereinabove set forth.

The primary feature of the invention resides
therefore in utilization of a single face platen
together with a cam having an active face for
each row of type respectively on the printing
plate, making it possible to pick up one line at
a time irrespective of the number of lines on the
plate being utilized by merely selecting the cor-
responding cam.

Having thus described the invention what is
claimed as new and desired to be secured by
Letters Patent is:

1. In a printing machine adapted for use with
a printing plate provided with a number of rows
of type, said machine having a reciprocable
roller platen provided with a single printing
strip, apparatus for reciprocating said platen to
and from a printing position with respect to said
plate, rocker means operably connected with said
apparatus for actuating the latter, structure in-
cluding a shiftable rack for oscillating the platen
in response to reciprocable movement thereof,
and a swingable, spring-loaded arm for shifting
said rack; the improvement which comprises
arm control mechanism for initially setting the
rack and the platen to render the single print-
ing strip thereof effective during successive
cycles of reciprocation of the platen upon a
different row of type on said plate, said mecha-
nism including a rotatable disc having a plu-
rality of peripheral cam faces successively en-
gageable with said arm as the disc is rotated to
swing the arm against the action of the spring
thereof, the radial distances between the cam
faces and the axis of rotation of the disc all be-
ing different; and means interconnecting said
rocker means and the disc for imparting step-
by-step rotative movement to the disc as the
platen is reciprocated.

2. In a printing machine adapted for use with
a printing plate provided with a number of rows
of type, said machine having a reciprocable
roller platen provided with a single printing
strip, apparatus for reciprocating said platen to
and from a printing position with respect to said

plate, rocker means operably connected with said
apparatus for actuating the latter, structure in-
cluding a shiftable rack for oscillating the platen
in response to reciprocable movement thereof,
and a swingable, spring-loaded arm for shifting
said rack; the improvement which comprises
arm control mechanism for initially setting the
rack and the platen to render the single print-
ing strip thereof effective during successive cycles
of reciprocation of the platen upon a different
row of type on said plate, said mechanism in-
cluding a rotatable disc having a plurality of
peripheral cam faces successively engageable
with said arm as the disc is rotated to swing the
arm against the action of the spring thereof,
there being a cam face corresponding to each
of said rows of type respectively, the radial dis-
tances between the cam faces and the axis of
rotation of the disc all being different; and means
interconnecting said rocker means and the disc
for imparting step-by-step rotative movement
to the disc as the platen is reciprocated.

3. In a printing machine adapted for use with
a printing plate provided with a number of rows
of type, said machine having a reciprocable roller
platen provided with a single printing strip,
apparatus for reciprocating said platen to and
from a printing position with respect to said
plate, rocker means operably connected with
said apparatus for actuating the latter, structure
including a shiftable rack for oscillating the
platen in response to reciprocable movement
thereof, and a swingable, spring-loaded arm for
shifting said rack; the improvement which com-
prises arm control mechanism for initially set-
ting the rack and the platen to render the single
printing strip thereof effective during successive
cycles of reciprocation of the platen upon a dif-
ferent row of type on said plate, said mechanism
including a rotatable disc having a plurality
of peripheral cam faces successively engageable
with said arm as the disc is rotated to swing the
arm against the action of the spring thereof,
there being a cam face corresponding to each of
said rows of type respectively, the relative radial
distances between the cam faces and the axis of
rotation of the disc being uniformly greater
from one cam face to the remaining cam faces;
and means interconnecting said rocker means
and the disc for imparting step-by-step rotative
movement to the disc as the platen is recipro-
cated.

4. In a printing machine adapted for use with
a printing plate provided with a number of rows
of type, said machine having a reciprocable roller
platen provided with a single printing strip, ap-
paratus for reciprocating said platen to and from
a printing position with respect to said plate,
rocker means operably connected with said ap-
paratus for actuating the latter, structure in-
cluding a shiftable rack for oscillating the platen
in response to reciprocable movement thereof,
and a swingable, spring-loaded arm for shifting
said rack; the improvement which comprises
arm control mechanism for initially setting the
rack and the platen to render the single print-
ing strip thereof effective during successive
cycles of reciprocation of the platen upon a
different row of type on said plate, said mecha-
nism including a rotatable disc having a plu-
rality of peripheral cam faces successively en-
gageable with said arm as the disc is rotated to
swing the arm against the action of the spring
thereof, there being a cam face corresponding to

each of said rows of type respectively, said faces of the cams being spaced at progressively and uniformly greater radial distances from the axis of rotation of the disc from one cam face toward the remaining cam faces in one direction along the periphery of the disc; and means interconnecting said rocker means and the disc for imparting step-by-step rotative movement to the disc as the platen is reciprocated.
